(57) **CLAIM**

The ornamental design for a screw driving tool, as shown and described.

DESCRIPTION

FIG. 1 is a first perspective view of the screw driving tool; FIG. 2 is a second perspective view of the screw driving tool;

FIG. 3 is a front view of the screw driving tool;

FIG. 4 is a rear view of the screw driving tool;

FIG. 5 is a first side view of the screw driving tool;

FIG. 6 is a second side view of the screw driving tool;

FIG. 7 is a top view of the screw driving tool;

FIG. 8 is a bottom view of the screw driving tool; and,

FIG. 9 is a bottom view perspective view.

The drawings include surface shading which illustrates contour and not surface ornamentation.

The broken lines in the above-described figures are for illustrative purposes only and form no part of the claimed design.

1 Claim, 9 Drawing Sheets
